Ms. 598

John H. Barth of Indianapolis, Ind.
Letters Patent No. 598 Dated Oct. 14th, 1853.

The schedule referred to in these Letters Patent, and making part of the same.

To all whom it may concern:

Be it known, that I, John H. Barth of Indianapolis in the County of Marion, and State of Indiana, have invented a new and original Design for Bedsteads, and I do hereby declare that the following is a full clear and exact description of the same; reference being had to the annexed drawings forming part of this specification, in which

Figure 1 is an elevation of main and interior posts, headboard and cornice.

Figure 2 is a similar view of foot board and interior post.

Figure 3 is a view of side piece and rail.

Figure 4 is a view of rail on opposite side.

In the several figures, but one half of each symmetrical

design is given: similar letters indicate the same part.

This bedstead consists of four main posts A, four interior posts B, head board C, foot board D, side board E, two end rails F, two side rails G, and cornice H, these several parts having the design and configuration of ornament as set forth in the following description:

The main posts A, which are of a square cross section between a' and b' have at bottom the foliage a, forming the foot, and between the bands c and c' the beads d, while above the band c are the leaves d', forming a base for the shaft a", which is surmounted with the mouldings b", under which are the beads c". Above a' the post A has a circular cross section made up of the mouldings e and e', and twisted shaft f, the whole surmounted with the foliage f'; the arrangement and configuration of the several ornaments being in detail as represented in figure 1.

The post B which rests upon the casting g has its base ornamented as seen at h, above which is the square shaft h' to which the rails F and G are attached. Above the shaft h' are the mouldings i and i', octagonal shafts k and k', conical shaft j, and fluted bead l; the whole surmounted with the cup l', containing the flame l", the details being as set forth in the drawings.

The head board C has the form seen at m surmounted with the spherical ornaments m', and embellished with the openings m" and m'" as shown in figure 1.

The foot board D is formed of the open scrolls n n' n", figure p and cap p' arranged and having the configuration set forth in figure 2.

The side board E bears the raised scrolls g and g' arranged and having the configuration shown in figure 3.

The side and end rails F and G, are each formed with a sunken panel x having at top and bottom the beads r', as set forth in the drawings.

The cornice H is made up as shown in figure 1, and otherwise ornamented, as seen at s and s' in the same figure.

What I claim as my invention or production and desire to secure by Letters Patent, is

The design, configuration, and arrangement of the several ornaments and mouldings on the posts, rails, head, foot, & side boards, and cornice, as fully set forth in this specification & annexed drawings forming a new and original design for bedsteads.
